US00D600235S

(12) **United States Design Patent**
Wada

(10) **Patent No.:** **US D600,235 S**
(45) **Date of Patent:** **** Sep. 15, 2009**

(54) **SPEAKER**

(75) Inventor: **Jo Wada**, Tokyo (JP)

(73) Assignee: **Sony Corporation**, Tokyo (JP)

(**) Term: **14 Years**

(21) Appl. No.: **29/300,200**

(22) Filed: **Feb. 29, 2008**

(30) **Foreign Application Priority Data**

Jan. 23, 2008 (JP) 2008-001208

(51) **LOC (9) Cl.** **14-01**

(52) **U.S. Cl.** **D14/217; D14/216**

(58) **Field of Classification Search** D14/204, D14/210–217, 172; 181/143–144, 147–148, 181/150–153, 157, 198–199; 381/300–303, 381/306, 332–333, 336, 345, 361–364, 386–388; D7/536; D6/491, 496; D21/803

See application file for complete search history.
